CLAIM

The ornamental design for a display panel or screen with graphical user interface, as shown and described.

DESCRIPTION

FIG. 1 is a front view of a display panel or screen with a graphical user interface showing a first embodiment of our new design;

FIG. 2 is a front view of a second embodiment thereof;

FIG. 3 is a front view of a third embodiment thereof; and,

FIG. 4 is a front view of a fourth embodiment thereof.

The outermost broken lines illustrate a display panel or screen and form no part of the claimed design. The remaining broken lines illustrate portions of the graphical user interface that form no part of the claimed design.
